UNITED STATES PATENT OFFICE.

AUGUSTUS M. SOSA, OF CINCINNATI, AND WILLIAM G. HOELSCHER, OF NORWOOD, OHIO, ASSIGNORS TO THE AMERICAN TOOL WORKS COMPANY, OF CINCINNATI, OHIO, A CORPORATION OF OHIO.

FEEDING MECHANISM FOR DRILLING MACHINERY.

Application filed June 13, 1927. Serial No. 198,426.

It is the object of our invention to provide novel means for quick release in the power feeding train for insuring a definite moment of release for accuracy in the depth of cut of the cutting tool on the drill-spindle; further, to provide novel means whereby the urge for release relation in the power feed is increased with increase in the power necessary to perform the feeding operation; further, to provide novel means for limiting the movement of the drill-spindle in feeding direction; further, to provide novel means for manual feeding of the drill-spindle; and, further, to provide novel safety means to prevent interference between the power feeding devices and the manual feeding devices, and the invention will be further readily understood from the following description and claims, and from the drawings, in which latter:

Fig. 1 is a front elevation of a drill-head mounted on a drill-arm, partly broken away.

Fig. 2 is a side elevation of the same.

Fig. 3 is a vertical section of the same, taken on the irregular line 3—3 of Fig. 2.

Fig. 4 is a vertical section of the same, taken in the plane of the irregular line 4—4 of Fig. 3.

Fig. 5 is a horizontal cross-section of the same, taken in the plane of the irregular line 5—5 of Fig. 3, and partly broken away.

Fig. 6 is a horizontal cross-section, taken in the plane of the line 6—6 of Fig. 4, and partly broken away.

Fig. 7 is a horizontal section, taken in the plane of the irregular line 7—7 of Fig. 4.

Fig. 8 is a vertical cross-section, taken in the plane of the line 8—8 of Fig. 4; and,

Fig. 9 is a detail view of the operating arm, partly in section on the line 9—9 of Fig. 1.

A usual drill-arm 21 supports a usual drill-head 22 adjustable laterally on the drill-arm, as by means of a handle 23 in train with a usual rack-pinion meshing with a usual rack 24 extending lengthwise of and secured to the drill-arm. The drill-arm may be the usual drill-arm of a usual drilling machine or of a so-called sensitive radial drilling machine. A drill-spindle 25, arranged for carrying a usual drilling tool in its lower end, is rotatable and slideable axially in the drill-head.

In the present exemplification there is a sleeve 31 journaled in bearings 32 in the drill-head, the sleeve having a pulley 33 thereabout and secured thereto, so as to rotate the sleeve, the pulley being rotated by a suitable belt suitably driven. The drill-spindle has spline key and groove connection 34 with the sleeve, so as to be rotated thereby and to have axial movement therein. The drill-spindle is rotatable and has suitable bearing connection in a rack-sleeve 35, movable axially in a bearing 36 in the drill-head and held non-rotatively therein, as by means of spline groove and key connection 37. This sleeve is provided with a rack 38 with which a pinion 39 meshes for feeding the rack, sleeve and the drill-spindle endwise.

The sleeve 31 has a pinion 43 fixed thereto, which meshes with a gear 44 fixed to a shaft 45 journaled in bearings 46 in the drill-head. A cluster gear 47, shown as comprising three gears, is shiftable axially on the shaft 45, and rotates with said shaft, as by suitable spline groove and key connection 48. The respective gears thereon are arranged to mesh with the respective gears, shown as three in number, on a gear cluster 51, fixed to a shaft 52, journaled in bearings 53, in the drill-head.

The gear cluster 47 is adjustable axially on its shaft by means of a handle 56 on a shaft 57 journaled in a bearing 58 in the drill-head. The shaft 57 has a pinion 59 thereon which meshes with a rack 60 of a rack-piece 61 having a fork 62 thereon, which is received in an annular groove 63 in the gear cluster 47. The rack-piece is movable axially on a rod 64 secured in bearings 65 in the drill-head. The rod 64 is provided with annular grooves 66, in which a spring-pressed positioning ball 67 is arranged to be respectively received for locating the gear cluster 47 in adjusted positions. The ball is received in one of said grooves at each intermeshing relation of the gear clusters and at an idle position of the gear cluster 47. When said ball is received in the second groove from the top, the gear-cluster 47 is in idle position, for leaving the train of gears beyond said gear-cluster idle.

The shaft 52 has a worm 71 rigid therewith, which meshes with a worm-wheel 72, rotatable loosely on a shaft 73 fixed in bear-

ings 74, 75, in the drill-head. A gear 77 is arranged to be operatively connected with and disconnected from the worm-wheel, as by means of a clutch 78, shown as a tooth 5 clutch, the teeth of which are respectively on the worm-wheel and on a clutch-collar 79. The clutch-collar and the gear 77 are fixed together, as by being an integral piece 10 slidable axially on the hub 80 of the worm-wheel and rotating normally loosely on said hub. The clutch-collar and the gear 77 are arranged to be moved axially on said hub for engagement of the clutch when it is desired to feed the drill-spindle by power, or 15 for disengagement of the clutch when a power feed is not desired.

A gear 81 meshes with the gear 77 and is rotatable on a stud fixed to the drill-head. The gear 81 meshes with a gear 83 fixed to 20 a shaft 84, journaled in bearings 85 on the drill-head. The shaft 84 has a bevel-gear 86 fixed thereto, which meshes with a bevel-gear 87, the hub of which carries the rack-pinion 39, and is fixed to a feed-shaft 88 25 journaled in bearings 89, 90, in the drill-head. The rack-pinion meshes with the rack 38 on the sleeve of the drill-spindle.

An operating arm 91 is fixed to a rock-shaft 92, rockable in bearings 93 in the drill-head. A fork 94 is fixed to said rock-shaft. 30 The arm 91, rock-shaft 92 and fork 94 form an operating lever for the clutch 78. A shoe 95 is pivoted to the fork on pins 96, the shoe being received in an annular groove 97 in the 35 clutch-collar. The operating arm 91 is arranged for manually engaging and disengaging the clutch. An arm 98 extends from the fork for automatically disengaging the clutch.

40 A projection 101 extends upwardly from the rack-sleeve 35, and is provided with a laterally extending lug 102, which projects into range with a projection 103 on the clutch-arm 98, for operating said clutch-lever and thereby releasing the clutch. The projection 103 is guided in a slot 104 in a bracket in the drill-head. A counterweight 45 106 is guided by a rod 107 fixed in the drill-head, the rod being received in a hole in the counterweight. The counterweight has one 50 end of a flexible band 108 secured thereto, the flexible band being received about a pulley 109 journaled on a stud fixed in the drill-head, the other end of said flexible band being secured to the upper end of the 55 upward projection 101.

The lug 102 is arranged to strike the projection 103 of the clutch-lever when the drill-spindle has been moved to fullest extent in 60 downward or outward direction, to move said clutch-lever so as to disengage the clutch and to serve as a limiting stop for axial movement of the drill-spindle.

Means are provided for selectively stopping 65 the feeding movement of the drill-

spindle and for positively arresting such feeding movement. Thus an arm 111 extends from the fork 94, and has on it a hook 112, which is arranged to coact with a stationary pin 113 fixed in the drill-head. A 70 cam-plate 115 is releasably and adjustably secured to the shaft 88 of the feed-pinion 39, as by having a securing plate 116 fixed to said shaft, which plate has a circular groove 117 therein. An outer index-plate 75 118 and the cam-plate 115 are journaled about the hub 119 of the plate 116. The groove 117 is shown as a dove-tailed groove having the dove-tail heads respectively of a positioning pin 120 and a clamp-bolt 121 80 received therein, the positioning pin and clamp-bolt being received through the cam-plate 115 and in the index-plate 118, the bolt being received through said index-plate and having a clamp-nut 122 thereon for 85 clamping the securing plate 116, the cam-plate 115 and the index-plate 118 together in adjusted positions.

The cam-plate is provided with a cam face 125 which is arranged to engage the arm 111 90 for disengaging the clutch when the cam-plate is clamped to rotate with the feed pinion 39.

The index-plate 118 has graduations 126 thereon, which register with a pointer 127 95 on the front of the drill-head. In setting the cam-plate, the index-plate and the cam-plate are unclamped and rotated together about the axis of the feed pinion 39 until the graduation mark on the index which 100 equals the depth of hole it is desired to drill is positioned in registry with the pointer 127, the drill-spindle having been previously fed downwardly so that the point of the drill engages the top face of the work in which 105 the hole is to be drilled. When now the plates 118, 115 and 116 are clamped together, and the drill is operated and fed into the work, the drill will be at its desired limit of feeding movement for drilling a hole of the 110 desired depth when the zero mark on the index coincides with the stationary pointer, at which point the tripping of the clutch takes place.

When such tripping takes place, the hook 115 115 engages the pin 113 and a lug 128 on the cam-plate engages the end of the hook, for definitely stopping the rotation of the feed-pinion and definitely limiting the downward travel of the drill-spindle. The lug 128, the 120 pin 113 and the interposed end of the hook 112 form a definite stop for the feed-pinion. The stationary pin 113 also prevents stress being applied upon the pivot-shaft 92 of the shifter-fork for the clutch-collar. 125

A spring plunger 131 has an inclined engaging face 132 which coacts with an oppositely inclined engaging face 133 on a lug 134 on the arm 98, for urging disengaging relation in the clutch. Upon engaged rela- 130

tion of the clutch the end of the plunger is received in a slot 135 on said lug for holding the clutch in properly engaged relation.

The combined clutch collar 79 and gear 77 5 rotate loosely and move axially on the hub 80. The gears 77, 81, have meshing teeth which are inclined with relation to their axes, these teeth being helical teeth. The 10 inclinations of the teeth are in such direction as to aid in release of the clutch and normally urge release of the clutch during power feeding of the drill. In the present instance the gear 77 rotates counter-clockwise, as indicated by the arrow in Fig. 5, 15 and the teeth are arranged along right-hand helices. This construction provides a very sensitive and definite release in the power driving means for feeding the drill, in order that a definite moment of release 20 of the feeding movement of the drill may be provided. In this construction the impulse for release of the clutch increases with increase in pressure necessary between the teeth of the gears for feeding the drill, so 25 that the greater the feeding pressure that is required, the greater will be the urge for release of the clutch. The combined gear and clutch also rotate loosely about the hub so that there is no lateral friction between 30 these parts.

Our improved device provides very sensitive and accurate releasing means for feeding the drill.

The adjustable stop may be employed 35 when feeding the drill manually, in which case, however, the clutch 78 remains in release relation, and the hook 112 remains in engagement with the pin 113, the stop face 128 engaging the lower end of the hook at 40 the desired limit of feeding movement of the drill-spindle.

If no adjustable stop for feeding movement of the drill-spindle by power or by hand is desired, the nut 122 is released, which 45 releases the cam-plate 115 and the index-plate 118 from the securing plate 116, and permits free rotation of the feed-pinion 39, throughout the range of feeding movement of the drill-spindle.

The shaft 84 is provided with a hand-wheel 141, shown as a pilot-wheel, by means of which the drill-spindle may be raised and lowered rapidly when the clutch 78 is disengaged, for raising the drill-spindle out of 50 the work, or to upward position, or for causing rapid descent of the drill-spindle, for instance, for contact of the end of the drill with the work.

The manual feeding movement of the 55 drill-spindle for feeding the drill into the work is preferably accomplished by means of an arm 142, which has a plunger 143 movable in a socket 144 in the arm. The plunger is provided with a tooth arranged 60 to engage between the teeth of a notch-plate

145, which is keyed to the shaft 84. A spring 146 in said socket normally urges engagement of the plunger with the notch-plate for connecting the arm 142 with the shaft 84. The manual feeding of the drill 70 into the work may be accomplished by one or more feeding movements of the operating arm 142, depending on the depth of hole to be drilled or other operation to be performed, the operating arm being released 75 from the notch-plate during return movements of the lever-arm to initial positions. Release from the notch-plate is automatically accomplished when the operating arm 142 is returned to normal position, as by 80 means of a release lever 150, pivoted on a pin 151 in the arm, and having a link 152 which is articulated with the release lever at 153 and is received through a slot 154 in the operating arm, and connected with 85 the plunger 143 as by a pin 155 for moving the plunger away from the notch-plate.

The release lever 150 is provided with a shoe 156 which has a notch 157 therein. A pin 158 is fixed to the drill-head. Upon 90 return of the operating arm 142 to initial position, the shoe is received under the pin and thereby automatically shifted for automatically releasing the plunger 143 from the notch-plate 145, the plunger being held in 95 release position by reception of the notch 157 about the releasing pin 158, which also holds the operating arm 142 in retracted position.

Our improved construction provides great 100 power for hand feeding of the drill, and insures a release of the hand-lever from the power driving means for the drill-feed, when it is desired to use the power feed for the drill-spindle.

Our improved device further provides very sensitive and accurate adjustable release of power feed from the drill-spindle for accuracy in lengths of feeding movements of the drill-spindle, and provides releasing means in which the urge for release 110 is increased as the feeding resistance is increased for accuracy and speed of release of feeding movement.

Our improved device further automatically releases the operating-arm for manual feed upon retraction of said operating arm and enables the change from hand feeding to power feeding, or vice versa, to be accomplished by the movement of a single 115 control part, namely, the operating arm 91, whereby the change from power feeding to hand feeding, or vice versa, is instantly obtained.

Having thus fully described our invention, what we claim as new, and desire to secure by Letters Patent, is:

1. In a drilling machine, the combination with a rotatable and axially feedable drill-spindle, of a train of gearing for axially 130

- feeding said drill-spindle, power means for driving said train of gearing, said train of gearing including relatively releasable driving elements and a pair of meshing helical gears, one of said releasable driving elements and one of said helical gears connected for combined movements in releasing direction, the helical teeth of one of said helical gears movable along the helical teeth of the other of said helical gears, and the helices of said helical teeth being inclined to urge said connected helical gear and said one of said releasable driving elements in release direction, means whereby to maintain said relatively releasable driving elements in driving relation, and means feedable with the feeding movement of the drill-spindle acting on said maintaining means to place said maintaining means in release relation.
2. In a drilling machine, the combination with a rotatable and axially feedable drill-spindle, of a train of gearing for axially feeding said drill-spindle, power means for driving said train of gearing, said train of gearing including a clutch and a pair of meshing helical gears, said clutch including a clutch-member and a complemental clutch-member, said first-named clutch-member and one of said helical gears connected for combined axial movements, the helical teeth of one of said helical gears movable axially along the helical teeth of the other of said helical gears, and the helices of said helical teeth being inclined to urge said connected helical gear and clutch-member axially away from said complemental clutch-member while rotative force in feeding direction is applied to said gears, thereby urging release of said clutch, clutch operating means, and a complemental tripping part for said clutch operating means, said complemental tripping part having operative connection with said drill-spindle for movement thereto complementary to the feeding movements of said drill-spindle.
3. In a drilling machine, the combination with a rotatable and axially feedable drill-spindle, of a train of gearing for axially feeding said drill-spindle, power means for driving said train of gearing, said train of gearing including relatively releasable driving elements and a pair of meshing helical gears, one of said releasable driving elements and one of said helical gears connected for combined movements in releasing direction, the helical teeth of one of said helical gears movable along the helical teeth of the other of said helical gears, and the helices of said helical teeth being inclined to urge said connected helical gear and said one of said releasable driving elements in release direction, an operating arm, releasable connecting means between said operating arm and said train of gearing for manually feeding said drill-spindle, and automatic releasing means for said connecting means operable to release said connecting means upon retracted position of said operating arm.
4. In a drilling machine, the combination with a rotatable and axially feedable drill-spindle, of a train of gearing for axially feeding said drill-spindle, power means for driving said train of gearing, said train of gearing including a clutch, a pivoted arm for releasing said clutch, a rotatable cam-part provided with a cam angularly adjustable about its axis of rotation, said cam rotatable in feeding relation with said drill-spindle, said cam coacting with said arm for releasing said clutch, and a stop for said arm between said cam and the pivot of said arm, said stop arresting movement of said arm toward said pivot, and said cam provided with a stop coacting with said arm in similar direction for definitely stopping feeding movement of said drill-spindle.

In testimony whereof, we have hereunto signed our names.

AUGUSTUS M. SOSA.

WILLIAM G. HOELSCHER.
